JESSE C. STRIBLING, OF ANDERSON, SOUTH CAROLINA, ASSIGNOR OF ONE-HALF TO
RALPH J. RAMER, OF ANDERSON, SOUTH CAROLINA

VALVE TOOL

Application filed April 5, 1929. Serial No. 352,804.

This invention relates to improvements in valve-displacing devices, such as are employed to facilitate the removal of poppet-valves. In a valve of this type, it is normally held closed on its seat by a coiled spring on its stem, interposed between an abutment and a washer held on the extremity of the valve stem by a cotter pin passing through the stem. As the spring is under compression, the pressure against the cotter pin prevents a ready withdrawal of the pin when it is desired to dismount the valve. One of the objects of the present invention is to provide a device that is operative to compress 15 the spring to relieve the cotter pin of the pressure so that it can be easily removed and the dismounting of the valve thereby facilitated. The device or tool for carrying out this object is described in detail hereinafter, 20 pointed out in the appended claims and illustrated by the accompanying drawing.

In the accompanying, in which similar reference characters designate corresponding parts,

Figure 1 is a side elevation of a tool embodying the invention, showing the same operatively mounted to compress the spring of a poppet-valve of an explosive engine, the proportionate size of the tool being excessive to illustrate the tool to better advantage.

Figure 2 is a sectional view on the line 2—2 of Fig. 1.

Figures 3, 4, 5 and 6, are detail perspective views, respectively showing the claw-actuating spring, the latch, the claw and the bracket.

Referring to the drawings in detail, 5 designates a part of an engine casing, in which is mounted the poppet-valve 6, the casing being broken away to show the valve. 40 On the stem 7 of the valve is a spiral spring 8 compressed between an abutment formed by the engine casing and the washer 9 held on the lower end of the valve stem by the cotter pin 10 passing through the stem. The 45 spring, under compression between the abutment and the washer, normally tends to hold the valve on its seat. When it is desired to dismount the valve for grinding and other purposes, the cotter pin must be removed 50 to free the valve stem from the washer

and spring so that the stem can be slipped through the casing part to displace the valve. To compress the spring preliminary to the removal of the cotter pin, the instant valve tool is provided and is particularly adapted 55 to the purpose.

The operative parts of the valve tool are mounted on a main frame or support comprising arms 11 and 12, respectively, angularly disposed to each other. With the tool 60 in operative position, as shown in Fig. 1, the horizontal arm 11 has a downwardly turned end provided with a shoe 13 adapted to engage the under side of the valve 6. On the vertical arm 12 is slidably mounted the 65 bracket 14. This bracket consists of a strip of metal bent at an intermediate part to form parallel sides in longitudinal extension of the bracket. Between these parallel sides is welded the elongated block 15 to hold the 70 sides in spaced relation and to stiffen the bracket. At an end of the bracket, the block 15 and the adjacent end wall of the bracket form a socket 16 fitting somewhat closely the arm 12 to maintain the bracket laterally 75 extended from said arm. In the inner edge of the arm 12 is a series of notches 17. A catch 18 is pivoted to the block 15 to engage the notches 17 to hold the bracket in its adjustments on the arm 12.

Mounted on the upper side of the bracket 80 14 is the claw 19 extending the same general direction as the bracket, the claw being U-shape in cross-section. At one end the claw enters between the sides of the bracket 14 85 above the block 15. A pin 20 passing through the sides of the bracket and the interposed end of the claw, pivots the claw to the bracket adjacent to the sliding connection of the bracket with the arm 12. At its free 90 end, which is forked as shown in Fig. 2, the claw extends beyond the outer end of the bracket. A spring 21 is pivoted at an intermediate part between the sides of the claw by the pin 22. This spring bears at its respective ends against the arm 12 and the claw 19 and normally tends to press the claw toward the bracket.

Straddling the outer end of the bracket 14 95 is the bifurcated lever 23, pivoted thereto by 100

the pin 24. This lever is angularly bent adjacent to its pivotal connection with the bracket to provide the comparatively long operating handle 25 and the comparatively short arm 26. Extending across the free end of the short arm is the pin 27 bearing against the claw 19, which enters between the sides of the arm to contact with the pin. The spring 21 tends to maintain the claw in contact with the pin 27 and when the lever is turned on the pivot 24, the short arm 26 effects a camming action on the claw so that the free end of the latter is moved to and from the shoe 13.

When the device is used to facilitate the removal of a cotter pin, the bracket 14 is adjusted on the arm 12 of the support so that the arm 11 and the claw 19 are approximately parallel with the shoe 13 positioned to contact with the upper side of the valve 6 and the claw opposite to the upper end of the valve stem 7. With the parts so adjusted and the handle 25 turned downward, the free end of the claw is forced between the washer 9 and the cotter pin 10 with the recessed end of the claw straddling the valve stem, and the shoe 13 is placed above the valve 6. With the several parts so adjusted and positioned, as shown in Fig. 1, by means of the handle 25 the operating lever 25 is turned to the dotted line position. This movement of the operating lever causes the short arm 26, through the pin 27, to effect a camming action on the claw 19 and forces the free end of the latter upward. This upward movement of the claw comprises the spring 8 so that the cotter pin 11 is relieved of the pressure of the spring and can be readily removed.

After the cotter pin has been removed, the operating lever 25 is turned back to the full line position and the device is detached from the valve. When this is done the valve can be readily removed from the engine casing. In replacing the valve, the device is employed to compress the spring so that the cotter pin can be readily inserted in the valve stem. With the tool mounted as shown in Fig. 1 and the operative parts moved to dotted line positions, the tool is clamped in place so that both hands can be employed to remove the cotter pin.

What I claim is:

1. In a valve-displacing device, the combination with a support comprising angularly disposed arms, one of said arms having an abutment at its extremity, the other arm having a series of notches spaced along said arm, of a bracket having a socket at one end slidable on the notched arm, a catch pivoted on the bracket to engage the notches of the notched arm to hold the bracket in its adjustments on said arm, a claw pivoted to the bracket to operate in opposition to the abutment, and a lever pivoted to the bracket to actuate the claw.

2. In a valve-displacing device, the combination with a support comprising angularly

disposed arms, one of said arms having an abutment at its extremity, of a bracket having a socket slidable on the other of said arms, said socket operating to maintain the bracket approximately parallel to the arm having the abutment, means for holding the bracket in its adjustments on the arm carrying said bracket, a claw pivoted to the bracket to operate at its free end in opposition to the abutment, a spring mounted on the claw and bearing against the support, said spring normally tending to press the claw toward the bracket, and a lever pivoted to the bracket and having an angularly disposed arm engaging the free end of the claw, said lever arm being actuated by movement of the lever to effect a camming action on the claw to move the latter toward the abutment against the action of the spring and automatically locking in this position.

In testimony whereof I affix my signature.

JESSE C. STRIBLING.
